UNITED STATES PATENT OFFICE.

WILLIAM J. WEINMAN, OF NICHOLASVILLE, KENTUCKY.

STUFFING-BOX.

No 902,352.

Specification of Letters Patent.

Patented Oct. 27, 1908.

Application filed April 15, 1908. Serial No. 427,169.

To all whom it may concern:

Be it known that I, WILLIAM J. WEINMAN, a citizen of the United States of America, residing at Nicholasville, in the county of Jessamine and State of Kentucky, have invented certain new and useful Improvements in Stuffing-Boxes, of which the following is a specification, reference being had therein to the accompanying drawing.

10 This invention relates to a stuffing box particularly designed for pulverizers, and the primary object of my invention is to provide a simple and effective split box applicable to any roller journal.

15 A further object of my invention is to reduce the number of parts of the stuffing box and provide a compact structure that will be strong and durable. To this end, I have devised a stuffing box for that type of 20 mill commonly known as the "Raymond mill", used for grinding and pulverizing various products, such as crude barytes. In connection with what is known in the trade as the Raymond mill a stuffing box is bolted 25 to the base of the housing of the journal of the roller, and its function is to prevent grease from flowing into the mill and to prevent grit or foreign matter from coming 30 in contact with the journal and bronze housing thereof.

Considerable trouble is experienced in connection with this box due to the construction thereof, the bolts becoming heated and breaking off, causing plates or certain parts 35 of the stuffing box to be precipitated into the mill. As the mill is entirely closed when operating, it is impossible to determine when the box has become disabled until some damage has been caused thereby.

40 I obviate the above defects by providing a stuffing box that will be presently described and then specifically pointed out in the appended claims.

45 Referring to the drawings forming a part of this specification, Figure 1 is a side elevation of my stuffing box as applied to a portion of a pulverizer, Fig. 2 is a side elevation of one of the sections of the stuffing box, Fig. 3 is a similar view of an adjoining section, Fig. 4 is a plan of my improved stuffing box, Fig. 5 is a longitudinal sectional view of the same, and Fig. 6 is a perspective view of a two-part follower used in connection with the box.

55 In the accompanying drawings, I have illustrated a portion of a grinding and pul-

verizing mill, particularly the housing of the journal 1 of the roller. The lower end of this journal is provided with a peripheral apertured flange 2, and secured to said flange 60 by bolts and nuts 3 is my split or sectional stuffing box.

Each section comprises a sleeve 4 having a semi-cylindrical flange 5 at one end and a casing 6 at the opposite end. The casing 6 65 is provided with oppositely disposed lugs 7 and 8, connected by bolts 10 and nuts 11. The apertured lug 8 is adapted to receive the stud bolt 10 of the adjoining section and be held in engagement therewith by a nut 11. 70 When the two sections are secured together by the stud bolts and nuts just mentioned, the flanges 5 can be secured to the flange 2 by the nuts and bolts 3. In the casing 6 of the stuffing box is located a two-part wood 75 follower, the parts 12 and 13 of said follower having ship-lap tongues 14, and coil springs 15, these springs bearing against the inner sides of the casing 6 for retaining the wood followers in engagement with the journal 16 80 of the mill. The ship-lap connection between the parts of the follower allows the springs 15 to take up the wear of said followers.

From the foregoing description taken in 85 connection with the drawings, it will be observed that I have devised a stuffing box that can be easily removed from the mill without taking out the rolls thereof. Approximately four parts constitute my stuffing 90 box and these parts are advantageously arranged, whereby it is impossible for the same to become disassembled during the operation of the mill.

I reserve the right to make such changes 95 in the size, proportion and minor details of my invention as are permissible by the appended claims.

Having now described my invention what I claim as new, is:—

1. A stuffing box comprising two sections or members each embodying a semi-cylindrical sleeve terminating at one end in a semi-circular flange and at the other end in a semi-circular casing of a greater diameter 105 than the sleeve and having an apertured lug at each end, bolts connecting said apertured lugs, and a two-part follower mounted in said casing and having ship-lap tongues, and springs arranged between the ends of said 110 follower and the inner wall of the casing.

2. The combination with a journal pro-

vided on one end with an annular apertured flange and a rotatable shaft extending into said journal, of a stuffing box comprising two counterpart sections each embodying a 5 semi-cylindrical sleeve terminating at one end in a semi-circular flange and at the other end in a semi-circular casing, the latter provided with oppositely-disposed lugs, means for securing the lugs of said sections 10 together, means for securing the flanged end

of said stuffing box to the flanged end of said journal, and a spring-pressed two-part follower arranged within the casing end of said stuffing box to engage said shaft.

In testimony whereof I affix my signature 15 in the presence of two witnesses.

WILLIAM J. WEINMAN.
